UNITED STATES PATENT OFFICE

128,365

DESIGN FOR A DISPENSING BOTTLE

Henry F. Daum, Tacoma, Wash., assignor to The Perfex Company, Tacoma, Wash., a corporation of Washington

Application February 25, 1941, Serial No. 99,213

Term of patent 7 years

To all whom it may concern:

Be it known that I, Henry F. Daum, a citizen of the United States, residing at Tacoma, in the county of Pierce and State of Washington, have invented a new, original, and ornamental Design for a Dispensing Bottle, of which the following is a specification, reference being had to the accompanying drawing, forming part thereof.

bottle showing my new design.

Figure 2 is a top plan view thereof.

I claim:

The ornamental design for a dispensing bottle,
as shown.

HENRY F. DAUM.
